UNITED STATES PATENT OFFICE.

RALPH R. McILVAINE, OF WILKINSBURG, PENNSYLVANIA.

ELECTRIC-LAMP SOCKET.

1,090,930.

Specification of Letters Patent. Patented Mar. 24, 1914.

Application filed July 16, 1913. Serial No. 779,236.

To all whom it may concern:

Be it known that I, RALPH R. McILVAINE, a citizen of the United States, residing at Wilkinsburg, in the county of Allegheny and State of Pennsylvania, have invented new and useful Improvements in Electric-Lamp Sockets, of which the following is a specification.

My invention relates to holders or sockets 10 for incandescent electric lamps and its object is to provide an extremely simple device of this character, from which a lamp cannot be removed without breaking the lamp and which retains all the necessary switch elements and terminals without the employment of screws or other special devices.

Referring to the accompanying drawings, Figure 1 is a central longitudinal section of a socket involving my invention; Fig. 2, a side view of the same with the cap, shell, and lamp removed; Fig. 3, a longitudinal section on the line III—III, Fig. 2; Fig. 4, a top view of Fig. 2; and Fig. 5, a side view of one section of the body of the socket.

On the drawings, 1 and 2 represent the halves of the base-plug, which constitute the body of the holder and are composed of porcelain or other insulating material. The said halves meet in a plane which includes 20 the longitudinal center of the lamp-holder, their lower ends being reduced in cross-section and provided with external screw-threads to receive one end of the spiral spring or socket member 3 which constitutes 25 the member for securing the halves of the base-plug together and the threaded socket for the threaded base 4 of the incandescent lamp 5. The spring or socket 3, the base 4 of the lamp, and the threaded end of the 30 base-plug are of such relative dimensions that the spring is slightly opened or put under strain when it is being screwed on the base-plug and when the lamp base is being screwed into the spring, the friction being 35 such as to allow the parts to be readily screwed together, but such as to make the grip of the spring on the base-plug and lamp-plug increase on any attempt to screw them apart. The convolutions of the 40 spring are not bound together, but are left free so that they can act as a brake on any reverse movement of the parts screwed into the same. Any reverse movement of either 45 plug tends by the friction on the spring to make the latter smaller and, therefore, to grip the plug harder.

6 is the metal shell provided with the insulating lining 7 which is slid over the body of the holder from the reduced threaded end toward the larger end. The larger end of the shell and lining have the usual slot 8 for the key 8'.

9 is the usual removable cap for the larger end of the shell. The shell extends out to the outer end of the spring or socket 3 and covers the end of the same as far as practicable so that no tool can be inserted in the shell to partially uncoil the spring and thereby permit the lamp to be screwed out.

As the bulb of the lamp is larger than the shell and as the lamp cannot be screwed out of the spring socket 3, it is necessary, in order to remove the lamp plug or base 4 from the socket, to break the bulb away 75 from its base. When this has been done, the shell can, after the removal of the cap therefrom, be slid off from the body of the lamp-holder, so that access can be had to the spring 3, which can be slightly un- 80 coiled by pressure against its free end, thereby permitting the lamp-base to be easily screwed out.

It is seen that my invention prevents the theft of lamps which constitutes a large 85 item of loss, particularly in establishments employing a large number of persons.

The members 1 and 2 are internally recessed at 10 to receive the contact block 11, carried by the stem of the key 8', the stem 90 having bearings or open recesses in the meeting faces of the said halves. Opposite faces of the contact-block, which is composed of insulating material, are provided with the flat contact strips 12 electrically 95 connected by an intermediate portion thereof or otherwise to the key-stem. The end of the stem opposite the finger piece 13 of the key is provided with the line terminal 14 carrying the binding screw 15. This 100 terminal may be kept in contact with the stem in various ways, but I have shown the stem provided with the annular groove 16. The terminal is provided with a hole fitting the said groove and preventing the removal of the terminal from the stem.

The center terminal 17 for the lamp consists of a strip of conducting spring metal having one end bent to form the flat head or contact 18 for the usual center lamp terminal. The strip has a reverse head, or loop 110 19 within the recess in the member 2, where

2
by a space 20 between the loop and the contact 18 is formed to receive the bottom wall of the said recess, one of the members being recessed, as at 21 to permit the terminal to extend from the said recess to the contact or head 18. The recess 21 is preferably of such dimensions as to cause the terminal to be firmly clamped between the members 1 and 2 when screwed into the spring 3. The inner end of the terminal 17 is bent so as to form a brush or contact finger 22 for engagement with the strips 12. There will, therefore, be two positions of the block 180° apart, at which the line terminals will be electrically connected, and two positions 90° from the other two positions at which the brush 22 will contact with the non-conducting material of the contact block and at which the line terminals will not be electrically connected, as will be readily understood.

The remaining line terminal marked 23 is provided with the binding screw 24 and has one end clamped between the spring 3 and the body of the socket, as shown in Fig. 2.

25 The threads on the sections 1 and 2 may have notches as shown on Fig. 5 to coöperate with teeth on the inside of the coil 3, the teeth on the coil also serving to hold the lamp plug 4 with greater force.

30 I claim—

1. In a holder for an electric lamp, an insulating body composed of longitudinal members provided with screw-threads on one end, a coiled spring into which the said body is screwed and by which the members are held together, a lamp terminal projecting through the center of the end of the body which is provided with the spring, and a rotatable key having a contact block rotatable in recesses in opposing faces of the members and having bearings in the meeting walls of the said members and in sliding contact with the inner end of the said terminal.
- 45 2. In a holder for an electric lamp, an insulating body composed of internally-recessed members, means for securing them together, a rotatable key provided with a stem having bearings in recesses in the opposing faces of the said member, and a contact block secured to the stem and provided with a con-

tact strip, a center lamp terminal having a bend fitting the lower wall of one of the recesses, a head below the outer bend, and a brush in one of the recesses and adapted to be engaged by the contact strip when the key is suitably operated.

3. In a holder for an electric lamp, an insulating body composed of internally-recessed members, means for securing them together, a rotatable key provided with a stem, and a contact block secured to the stem and provided with a contact strip, a center lamp terminal having a bend fitting the lower wall of one of the recesses, a head below the outer bend, and a brush in one of the recesses and adapted to be engaged by the contact strip when the key is suitably operated.

4. In a holder for an electric lamp, an insulating body composed of internally-recessed members, means for securing them together, a rotatable key provided with a stem, and a contact block secured to the stem and provided with a contact strip, a line terminal secured to the stem, and a center lamp terminal held in position by the said members.

5. In a holder for an electric lamp with a threaded plug, a body comprising a plurality of longitudinal members provided at one end with screw-threads, a coiled spring into which the said members are screwed and by which they are held together, and a line terminal held by and between the said spring and the said body.

6. In a holder for an electric lamp with a threaded plug, a body provided at one end with screw-threads, a coil spring into which the said body is screwed, and a line terminal held by and between the said spring and the said body.

7. In a holder for an electric lamp, a body member having notched threads, and a coil spring socket member having toothed convolutions in the threads on the body member.

Signed at Pittsburgh, Pa., this 11th day of July, A. D. 1913.

RALPH R. McILVAINE.
